UNITED STATES PATENT OFFICE

2,028,166

APPARATUS FOR COKING LIQUID RESIDUUMS

Clifton John Pratt, St. Louis, Mo., assignor, by mesne assignments, to J. P. Devine Manufacturing Co., Inc., Mount Vernon, Ill., a corporation of Illinois.

Application August 6, 1931, Serial No. 555,401
Renewed September 24, 1934

1 Claim. (Cl. 202—117)

This invention relates to an apparatus for forming coke, and with regard to certain more specific features, to the method of, and apparatus for forming coke from the residuums of an oil refinery.

Among the several objects of the invention may be noted the provision of a process for continuously converting heavy residuums into coke; the provision of a process of the class described which subjects said residuums to a cracking and distilling operation and then to a coking operation; the provision of a process of the class described in which superheated steam is admitted to dry and render the product porous; the provision of a process of the class described which is continuous, economical, and which produces a high grade coke with simplified apparatus. Other objects will be in part obvious and in part pointed out hereinafter.

The invention accordingly comprises the elements and combinations of elements, steps and sequence of steps, features of construction and synthesis, and arrangements of parts, which will be exemplified in the structures and processes hereinafter described, and the scope of the application of which will be indicated in the following claim.

In the accompanying drawings, in which are illustrated one or more of various possible embodiments of the invention,

Fig. 1 is a vertical longitudinal section of a coking unit embodying the invention;

Fig. 2 is a top plan view of the unit of Fig. 1; Fig. 3 is a vertical section taken on line 3—3 of Fig. 1, taken through a distilling chamber; and,

Fig. 4 is a vertical section taken on line 4—4 of Fig. 1, taken through a coking chamber.

Similar reference characters indicate corresponding parts throughout the several views of the drawings.

The drawings show a unit adapted to convert heavy hydrocarbon residuums, as for instance those obtained from an oil refinery into coke, gas and some relatively heavy hydrocarbon fractions. Formerly in thus treating residuums apparatus was used which carried out the process by a batch method and the batch process had the disadvantages commonly associated with all such types of batch units, namely, poor thermal efficiency, loss of time, as well as the necessity of employing larger units per unit of output. Further, with the former batch process, certain cracking and other chemical processes deposited graphite or the like on the interiors of the stills, there-

by reducing the coefficient of heat transfer of the stills. This resulted because the same surface that was used for distilling the residuums was also used for coking the residuums.

I have overcome the above difficulties by providing a continuous process and by providing different surfaces for the initial distillation and the final coking.

Referring now more particularly to Fig. 1 the apparatus for carrying out my method comprises a charging and distilling chamber A, and a coking chamber B. The chamber A has a trough-shaped steel floor or bottom 3, which slopes downwardly to the coking chamber B. The bottom pan 3 is supported by I-beams 5. Above and on the sides of the pan 3 is a wall 7 comprising a heat insulating brick wall 9 provided with a steel shell lining 11. Leader pipes 13 conduct vapors rising from the chamber A to a main header or manifold 15 which conducts the vapors to a bubble tower 17.

The heavy residuums to be coked are introduced into chamber A through pipes and nozzles 19 which lead off from a header 21 (Fig. 3). The flow of the liquid residuum is controlled by valves 20. Inasmuch as the residuums are pre-heated before being sprayed into the chamber A through the nozzles 19 and inasmuch as the chamber A is also heated, a part of the material charged is immediately cracked and/or vaporized and drawn off through the leader pipes 13. The stock charged which is not thus immediately vaporized falls to the bottom 3.

A chain arrangement 23, which comprises plates or partitions 25, shaped to the contour of the floor 3, and which are joined together by a suitable chain linkage 27, is adapted to keep the residuum which falls to the floor, moving toward the end of the chamber A. The linkage 27 also has wheels 26 which are provided to support the chain on a track 28. A motor 29 continuously drives the chain arrangement.

The chamber A is heated by gases from the furnaces of the coking chamber. These gases, by a passage 31, enter the passage 33, comprising the side walls 7, a brick partition 35 and the floor plate 3 and thereby heat the floor plate 3 to continuously crack and/or distill the stock which falls thereon. The gases leave the passage 33 through a breaching 37 and enter a chimney 39.

In the chamber B the final coking operation is carried out. The top and side steel lined walls 7 continue over this chamber. The floor comprises a moving chain grate type of conveyor 41 sup-

ported by a number of I-beams 43. The conveyor receives the partially distilled material from the chamber A, and carries it through the chamber B where it is coked. This chamber is heated by furnaces 45 which burn gas or oil and which heat the top 47 of the furnace to an incandescence. The grate 41 thus receives the heat from the incandescent surface 47. Nozzles 49 are positioned along the chamber to permit the introduction of 10 superheated steam.

A chamber C is next to the chamber B and is divided therefrom by a partition 67 which has a tongue 71 hanging down. In this chamber superheated steam is introduced through nozzles 51 15 both above and below the grate 41.

A quenching chamber D is next to the chamber C and in this chamber water is sprayed over the coke on the grate 41 from nozzles 53. A partition 69, with a flap or tongue 73 separates the 20 chambers C and D.

The chamber B, as well as chamber A, is connected by lead pipes 13 with the main header 15.

The chain grate 41 is driven by means such as a motor 55. It is to be understood that either 25 the speed of the motors 29 and 55 is made variable or adjustable driving means is provided between the motors and their respective chains whereby the speed of the chains may be regulated.

30 A car 57, placed outside the unit, receives the coke from the grate 41. A scraper 61 is provided to insure complete removal of the coke from the grate 41.

A walk 59 is run around the greater part of the 35 unit and enables manual adjustment of the various valves and inspection of the operation. The steam lines 49 and 51 are provided with valves for regulating the flow of the steam.

The operation of the coking unit when running 40 on a preheated liquid hydrocarbon residuum is as follows:

After the whole unit has been brought up to the predetermined required temperatures, preheated heavy oil residuum from, for example an 45 oil cracking plant, is brought into the header 21, from which it flows into the chamber A through the nozzles 19, the flow being regulated by the valves 20. The hot residuum oil on being sprayed into the chamber A partially cracks, some of the 50 lighter fractions rising in the form of vapor, and the remainder falling to the floor plate 3. The fractions of the oil falling to the floor plate 3, partially fills the compartments formed by the partition plates 25, and as the partition plates 55 move forward under the action of the chain 23, this oil is moved forward toward the end of the chamber A. Inasmuch as the floor plate 3 is subjected to considerable heat by means of the hot gases passing through the passage 33, a large 60 portion of the remaining fractions of the oil which fall to the floor plate is cracked and/or distilled off, so that by the time the oil reaches the end of the floor plate 3 it has become a heavy semi-solid material.

65 As shown in Fig. 1, the nozzles 19 are only provided over about half the length of the floor plate 3, thereby leaving a substantial area for the distilling of the oil which falls to the floor plate 3. The vapors which are thus distilled off from the 70 liquid combined with the vapors formed at the initial cracking and vaporization as the stock is sprayed into the chamber A from the nozzles 19, and pass through the main header 15 to the bubble tower 41.

75 The semi-solid material which leaves the

chamber A, falls onto the conveyor 41 and is carried through the coking chamber B. During the passage through the chamber B the remainder of the vapors contained in a semi-solid material are distilled off, leaving only coke on the conveyor 41 at the point at which the final product is extracted from the conveyor 41. 5

While thus passing through chamber B, the material is subjected to the action of superheated steam which enters the chamber B through the 10 nozzles 49, the flow of the steam being controlled by suitable valves 50. This steam during the coking operation helps to dry the material at a lower temperature, at the same time producing a more porous product. Just before the product or 15 material reaches the quenching chamber D, it passes through a steam chamber C in which large quantities of superheated steam is introduced from the nozzles 51 located above and below the moving grate 41. This introduction of the large 20 quantities of superheated steam substantially removes any volatile compounds which may be left. The coke now passes from chamber C into the quenching chamber D at which point cold water from the nozzles 53 is sprayed over the coke to 25 cool it down to a temperature in which it will not burn when it is extracted from the chamber.

The cold quenching water also serves to cause separation of the coke from the chain grate, so 30 that as it passes out of the caking chamber and the quenching chamber it freely falls off from the grate. However, any coke which may stick to the grate is removed by the scraper 61.

As hereinbefore pointed out the material while 35 passing through chamber B is heated by means of the flat incandescent arch 47 which is raised to an incandescence by means of the furnaces 45 in which gas or oil or the like is burned. The hot combustion gases leaving the furnaces 45 passes through a passage 63 (Fig. 2) and enters 40 the passages 31 and 33 to heat the floor plate 3.

The vapors from chamber B, which comprise 45 steam and hydrocarbon vapors combine with the vapors from chamber A in the main 15 and enter the bubble tower together. In the bubble tower 45 the hydrocarbons are fractionated, the lighter ones being taken out at the top and passed through a line 65 to a jet condenser 67, and these lighter fractions are afterwards separated from the water introduced into the jet condenser 67. 50 The heavier fractions are either continuously or intermittently removed from the base of the bubble tower, the operation not being shown inasmuch as this removal is known in the art. 55

The jet condenser is used to create a slight 60 vacuum throughout the main 15 and in the chambers A and B in order to prevent the escape of any hydrocarbon vapors through the steam and water chambers C and D and at the point where the grate 41 leaves the chamber B. By thus creating a partial vacuum in chamber B a small amount of air is continuously drawn in and positive prevention of any escape of gas is prevented.

It is to be understood that the temperatures 65 of the various chambers, as well as the rate of flow of the preheated oil residuum into the chamber A, and of steam into the chamber B and the rate of travel of the conveyors 23 and 41 is regulated to obtain optimum operating conditions, 70 and the values for the various flows and rates is not specified in that for different residuums and for different preheats different operating conditions would be required. It is further to be understood that either manual or automatic con- 75

tral may be provided to obtain optimum operating conditions.

One of the numerous advantages of my process of coking residuums is that it is continuous, and accordingly may be continuously run in cooperation, for instance, with a cracking unit, and in this way a large amount of heat is saved because there is no substantial time lag between the time that they leave the cracking still and enter the coking plant. Furthermore, by means of continuous operation it is possible to effect considerable saving in the usual heat loss in a batch coking operation. A further advantage of the continuous operation is that a smaller unit may be used per unit weight of output, inasmuch as the whole unit is working at all times, and at no time is a portion of the unit inactive.

For purposes of conciseness herein the section A can be referred to as a primary distilling section, section B a secondary distilling and coking section, section C as a drying section and section D as a cooling or quenching section.

In view of the above, it will be seen that the several objects of the invention are achieved and other advantageous results attained.

As many changes could be made in carrying out the above constructions, compositions, and

processes without departing from the scope of the invention, it is intended that all matter contained in the above description or shown in the accompanying drawings shall be interpreted as illustrative and not in a limiting sense.

5

I claim:

Apparatus for coking relatively heavy liquid residuums comprising a distilling chamber having a stationary heated floor, means introducing said liquid residuums into said chamber so as to fall upon said floor, means within said chamber continuously scraping the residuums from said floor and pushing the residuums in a direction towards the end of said chamber, a coking chamber receiving the residuums from the end of said distilling chamber, said coking chamber having as a floor a continuously moving grate on to which the residuums fall as they enter said coking chamber, and which carries the residuums through the length of the said coking chamber, 20 and furnaces below the residuum-receiving portion of said grate, said furnaces exteriorly heating both of said chambers, but maintaining said coking chamber at a temperature higher than that of the distilling chamber.
